Primary Examiner — Holly H Baynham*Assistant Examiner* — Rashida C. Walshon(74) *Attorney, Agent, or Firm* — Hemingway & Hansen, LLP; D. Scott Hemingway(57) **CLAIM**

The ornamental design for a sandal, as shown and described.

DESCRIPTION

FIG. 1 is a bottom perspective view of a sandal showing our new design;

FIG. 2 is a bottom view thereof;

FIG. 3 is a top view thereof;

FIG. 4 is a medial side view thereof;

FIG. 5 is a lateral side view thereof;

FIG. 6 is a front view thereof;

FIG. 7 is a back view thereof; and,

FIG. 8 is a top perspective view thereof.

1 Claim, 6 Drawing Sheets(56)
